UNITED STATES PATENT OFFICE.

PAUL SZATHMÁRY, OF CLARENCE, NEW YORK.

CONVEYER FOR MOLTEN METAL.

1,018,217.

Specification of Letters Patent. Patented Feb. 20, 1912.

Application filed October 30, 1911. Serial No. 657,403.

To all whom it may concern:

Be it known that I, PAUL SZATHMÁRY, a subject of the King of Hungary, residing at Clarence, in the county of Erie and State of New York, have invented certain new and useful Improvements in Conveyers for Molten Metal, of which the following is a specification, reference being had therein to the accompanying drawing.

10 This invention relates to a conveyer for molten metal, and the primary object of my invention is the provision of a novel form of conveyer for conveying moving metal from a furnace to a mold within a soaking pit.

Another object of this invention is to provide a sectional lined conveyer that can be easily and quickly opened and the interior thereof cleansed.

20 A further object of this invention is to provide a stationary trough with a movable cover and to arrange the trough in a manner that permits of the rapid discharge of the contents of the trough into a series of molds.

With the above and other objects in view, the invention resides in the novel construction, combination and arrangement of parts to be hereinafter specifically described and then claimed.

Reference will now be had to the drawing, wherein:—

Figure 1 is a side elevation of the conveyer, and Fig. 2 is an enlarged cross sectional view of the same.

40 The reference numeral 1 denotes an elevated furnace of a conventional form, the furnace being diagrammatically illustrated owing to the fact that various kinds of furnaces now employed can be used in connection with my improved conveyer.

Arranged in front of the furnace are a plurality of stepped supports 2 having the upper ends thereof provided with heads 3 for supporting the lower semi-cylindrical inclined section 4 of the conveyer. The section 4 of the conveyer has the longitudinal edges thereof provided with lateral flanges 5 and secured to said lateral flanges by bolts 6 and nuts 7 is a semi-cylindrical section or

cover 8, the sections 4 and 8 coöperating in providing a cylindrical structure. The sections 4 and 8 are lined with a non-fusible material 9, as fire clay or bricks. The section 4 is provided with openings 10 through which extend spouts 11 carried by the lining of the section 4 and made of a material similar to said lining. The spouts 11 are arranged at the lower end of the conveyer above a soaking pit 12 containing molds 13. Molten metal admitted to the conveyer from the furnace by the spout 14 passes downwardly through the conveyer and through the openings of the spouts 11 into the molds 13.

On account of having to renew the non-fusible material 9 lining of the conveyer, also on account of the conveyer not being continuously used and crustations forming upon the lining, it is necessary that the section or cover 8 be removed. For this purpose a traveling crane 15 is arranged above the conveyer, the crane having a hoisting drum 16 provided with cables or chains 17 connected to the section or cover 8 of the conveyer. The traveling crane is of the ordinary and well known type, and is employed for lifting the section or cover 8 off of the section 4, when the lining of said sections are to be renewed or cleansed. The crane can also be employed for bodily lifting the conveyer from the supports 2 and the molds 13 from the soaking pit.

What I claim is:—

A portable conveyer for molten metal comprising a pair of oppositely disposed semi-cylindrical sections having longitudinal extending flanges, the flanges of one section abutting against the flanges of the other section thereby providing an elongated hollow cylindrical member, means for shiftably connecting the flanges of one section to the flanges of the other section, said member, when in an operative position normally depending at an inclination, said lower member having disposed throughout the lower half portion thereof a series of openings, a cylindrical non-fusible lining engaging the inner face of each of said sections and having the lower portion thereof

provided with integral depending spouts of the same material, said spouts communicating with the interior of the lining and extending through and depending from the 5 openings in the lower of said sections, and means whereby a conveying device can be coupled to the upper of said sections for transporting said member.

In testimony whereof I affix my signature in the presence of two witnesses.

PAUL SZATHMÁRY.
